UNITED STATES PATENT OFFICE.

AUGUSTUS J. EAVES, OF NEW YORK, N. Y., ASSIGNOR TO WESTERN ELECTRIC COMPANY, INCORPORATED, OF NEW YORK, N. Y., A CORPORATION OF NEW YORK.

MULTIPLE SWITCH.

1,422,549.

Specification of Letters Patent.

Patented July 11, 1922.

Application filed August 14, 1918. Serial No. 249,820.

To all whom it may concern:

Be it known that I, AUGUSTUS J. EAVES, a citizen of the United States, residing at New York, in the county of New York, State 5 of New York, have invented certain new and useful Improvements in Multiple Switches, of which the following is a full, clear, concise, and exact description.

This invention relates in general to multiple switches and more particularly to a 10 multiple switch especially suitable for use in connection with adjustable condensers and rheostats.

In connection with various communicating systems there exists a considerable demand for a variable condenser having a relatively large capacity but adjustable within small steps and to meet this demand it has been the customary practice to supply a 15 switching arrangement equipped with a large number of small condenser units which can be successively connected in parallel across a pair of line terminals. Such an arrangement, however, is not only needlessly expensive 20 because of the large number of condenser units required, but in many cases it is too bulky to satisfactorily meet other requirements of the service. Again in connection with variable resistances or rheo- 25 stats, there is a demand for a device having a wide range but variable in steps of small value. To attain the desired range by employing the units of small value would result in a piece of apparatus which is both ex- 30 pensive and excessively large. To overcome these objections it is an object of the present invention to provide a multiple switch where- 35 by only a small number of units of the minimum value will be required, these units being automatically grouped with units of large 40 value in such a manner as to permit an adjustment over the entire range of the apparatus in steps always of the minimum 45 value. Another object of the invention is to provide a switching arrangement for a variable condenser or rheostat which is small in size, cheap to manufacture, and suitably arranged for installing in such a manner that it may easily be manipulated to 50 vary and indicate the capacity or resistance between line terminals.

To accomplish these objects a feature of the invention resides in employing a multiple switch so arranged as to successively 55 connect in circuit, the units of minimum

value which will be automatically disconnected from circuit when a unit of larger value is picked up. Another feature consists in providing a multiple switch equipped with contact plates at two different decks or 60 levels. These and other features will be described in the specification and more particularly pointed out in the appended claims.

In the accompanying drawings, Fig. 1 is a top view of the switching arrangement embodied in this invention and provided with a suitable casing; Fig. 2 is a top view of the switch of Fig. 1 with the casing removed; Fig. 3 is a side view of the switch shown in Fig. 2; Fig. 4 is a diagrammatic view showing the switch of Fig. 2 connected with the necessary condenser units; Fig. 5 is a diagrammatic view of a modified form of switch provided with suitable condenser units and equipped with an arrangement permitting a 70 larger range; and Fig. 6 is a top view of the switch of Fig. 5 equipped with a suitable casing.

Referring now more particularly to Figs. 1 to 4, there is provided an annular member 10 of suitable insulating material and having a portion cut away, as shown at 11-11. Mounted within the annular member 10 is a rotatable disc-shaped member 12, also of insulating material and having a portion of its periphery cut away to provide a lower level or deck extending entirely around the disc and in a plane with the recessed portions 11-11, while the upper surface or deck is in the plane of the upper surface of member 10. A commutator segment 13 of brass or other suitable conducting material is securely positioned in the edge of the upper deck or member 12, its upper surface being flush therewith. Similarly positioned in the lower level are the segments 14, 15 and 16 which are also of conducting material, and are insulated from each other. A handle 17 suitable for rotating the member 12 is secured thereto by the bolt 18 and nut 19, the bolt extending through member 12 and the metal plate 20 in which it is journaled and fastened by means of nuts 9, 9. Radially mounted on the recessed portion 11 of the annular member are the brushes or contact springs 21 to 31, inclusive. These springs which are insulated from each other are secured to the annular member 10 by means of the screws 54 and nuts 55, being also pinned to prevent them from turning. The free 100

ends of these springs are adapted to bear against the segments 14, 15 and 16 located on the outer and lower edge of member 12 and perform the various switching arrangements 5 in the manner to be described hereinafter. Also radially mounted on the upper surface of member 10 are the brushes or springs Nos. 32, 33 and 34, the free ends of which are adapted to bear against the upper surface 10 of disc 12 and the segment 13 mounted flush therewith. A casing 56 is provided to protect the apparatus from dust and moisture or mechanical injury. This casing which is arranged to be mounted by screws passing 15 through the mounting brackets 57-57 is provided on its inner periphery with a graduated scale over which sweeps a pointer 36 secured to the handle, when the latter is turned. Three standards or spacing members 52, 52 are provided to insure the proper separation when the apparatus is mounted. As shown in Fig. 4, the springs 22 to 31, inclusive, which bear on the lower level, are electrically connected to condenser units 38 25 to 47, respectively. These units are of small capacity, $\frac{1}{16}$ m. f. being chosen in the present case. The springs 32 and 34 which bear upon the upper level are connected respectively to condenser units 48 and 49, each of 30 1 m. f. capacity, and springs 21 and 33 are connected to a line terminal 50. The other line terminal 51 is connected in common to one terminal of each condenser unit. In the 35 position shown, the connections from terminal 50 would be open at springs 21 and 33 and the pointer 36 would therefore be opposite the zero mark on the scale, indicating zero capacity. Rotating the handle 17 in a clockwise direction from this position causes 40 segment 14 to engage springs 21 and 22, thereby connecting condenser 38 which is of $\frac{1}{16}$ m. f. capacity between terminals 50 and 51. Additional movement of handle 17 in the same direction increases the capacity 45 between the line terminals in $\frac{1}{16}$ m. f. steps up to the point where springs 21 to 30 are all in engagement with segment 14, thereby connecting condensers 38 to 46 in parallel across the line terminals and giving a total 50 capacity of $\frac{9}{16}$ m. f. Upon the next step, however, segment 14 leaves spring 21, thereby disconnecting condensers 38 to 46, but at the same time segment 13 has progressed far enough to bridge springs 32 and 33 and 55 in so doing connects condenser 48, which is of 1 m. f. capacity, between the line terminals. Upon further rotation the condensers 38 to 46 are again successively connected across the terminals by the springs 21 to 30, being engaged by the segment 15. During 60 this period, however, the springs 32 and 33 remain in contact with segment 13, hence the capacity between terminals 50 and 51 is increased in $\frac{1}{16}$ m. f. steps until spring 30 65 is engaged by segment 15, at which time the

total capacity between terminals will be $1\frac{9}{16}$ m. f. At the next step segment 15 leaves spring 21, thereby again disconnecting the $\frac{1}{16}$ m. f. condensers, but at the same time the segment 13 has advanced to the point where it engages spring 34 as well as springs 32 and 33, thereby connecting condenser 49 which is of 1 m. f. capacity in parallel with condenser 48, also of 1 m. f. capacity, between the terminals. As the handle is rotated further, segment 16 engages springs 21-31, thereby connecting the $\frac{1}{16}$ m. f. units between the terminals in the same manner as already described, and in parallel with the two 1 m. f. condensers. It will be noted 75 that the length of segment 16 is sufficient to engage spring 31 as well as springs 21-30, thereby connecting condensers 38-47 and giving a total capacity of 3 m. f. between line terminals, this capacity having been 80 reached in steps of $\frac{1}{16}$ m. f. 85

In Fig. 5 there is shown a modified type of switch suitable for obtaining a total capacity of 11.9 m. f. in steps of $\frac{1}{16}$ m. f. each. This switch is provided with an annular member 60 having a recessed portion in which are mounted the radial contact springs 61 to 70, inclusive, the free ends of these springs being adapted to bear against the segments 71, 72, 73 and 74 located in the 95 lower and outer edge of the rotating member 75. Located upon the upper surface of the annular member 60 are the springs 76, 77, 78, 79, 80, 81, 82 and 83, the free ends of which are adapted to bear upon the upper 100 level of the rotatable member 75 and engage the segment 85 mounted therein. The springs 62 to 70, inclusive, are connected to condenser units 85 to 93, respectively, each being of $\frac{1}{16}$ m. f. capacity. The springs 76 105 and 79 are joined together and connected to the condenser 94 which is of 1 m. f. capacity. The springs 80 and 83 are likewise joined together and connected to a condenser 95 of 1 m. f. capacity. Spring 82 is connected to 110 condenser 96 of 2 m. f. capacity. Springs 61, 81, 78 and 77 are connected to one of the line terminals 97, while the other line terminal 98 is connected in common to one terminal of each of the condensers. 115

Secured in the under side of rotatable member 75 is a pin 100 which is adapted once in each revolution to engage a switching device 101, this device being made rotatable by journaling the shaft 102 in the 120 under side of the annular member 60. Upon the rotation of the switching device 101 its projecting arm 109 is adapted to sweep over contacts 103 and 104 to each of which is connected a condenser unit of 4 m. f. capacity. The other terminals of these condensers are connected in common to line terminal 98 and the switching device is electrically connected to line terminal 97. 125

The apparatus is shown in a position for 130

zero capacity. Upon movement of the rotatable member in a clockwise direction, segment 71 engages springs 61 to 70 in order, thereby successively connecting condenser 5 units 85 to 93 between the line terminals 97 and 98 in the same manner as described in connection with the arrangement shown in Fig. 4, and thus giving a total capacity of 1.9 m. f. in steps of $\frac{1}{16}$ m. f. each. At the 10 next step segment 71 leaves spring 61, thereby disconnecting the condensers 85 to 93, inclusive, from the terminal 97, but at the same time segment 85 on the upper level of the movable member has advanced to a point 15 where it bridges the springs 76 and 77, thus connecting the condenser 94 of 1 m. f. capacity between the line terminals. Upon further rotation the segment 72 bridges contact springs 61 to 70, thus successively connecting condensers 85 to 93 in parallel with the condenser 94, and giving a total capacity of 1.9 m. f. between the line terminals. 20 At this point segment 85 has advanced to the point where it bridges springs 78 and 25 79 as well as springs 76 and 77. At the next step segment 72 leaves spring 61, thereby disconnecting the nine $\frac{1}{16}$ m. f. condensers. At this point segment 85 has advanced sufficiently far to leave spring 76 and engage 30 spring 80, thereby connecting condensers 94 and 95 each of 1 m. f. capacity between the line terminals. On further rotation the segment 73 engages springs 61 to 70, in order, thereby connecting condensers 85 to 93 and 35 making a total capacity of 2.9 m. f. connected between the line terminals. At the next step segment 73 leaves spring 61, thereby disconnecting the nine $\frac{1}{16}$ m. f. units, and at the same time segment 85 has advanced 40 to the point where it leaves spring 79 and engages springs 81 and 82, thus disconnecting condenser 94 and connecting condenser 96 which is of 2 m. f. capacity between the terminals and in parallel with condenser 95. 45 Further rotation causes segment 74 to engage springs 61 to 70 and to connect condensers 85 to 93 between the terminals in successive order. When segment 74 engages spring 70, the rotating circular disc has been 50 rotated thirty-nine steps out of a total of forty steps for a complete revolution, therefore at the next step condensers 85 to 96 are disconnected from the line terminals and the rotating member is again at its initial 55 position. However, during the fortieth step, the pin 100 secured to the rotating member 75 has engaged the left-hand arm of the switching device 101 and caused its contact member 109 to engage contact 103, 60 thereby connecting condenser 105 which is of 4 m. f. capacity directly between line terminals 97 and 98. As the rotating member is further revolved, the operation is the same as for the first revolution with the exception that condenser 105 is at all times 65 bridged between the terminals. During the second revolution therefore, the capacity between terminals is increased in $\frac{1}{16}$ m. f. steps from 4 m. f. to 7.9 m. f. At the fortieth step of the second revolution the pin 100 strikes 70 the middle arm of switching device 101 and causes contact arm 109 to engage the contacts 103 and 104, thereby connecting condenser 106 which is also of 4 m. f. capacity in parallel with condenser 105 between terminals 97 and 98. Therefore, during the third revolution of the member 75, the capacity between terminals is increased in $\frac{1}{16}$ m. f. steps from 8 m. f. to 11.9 m. f. Obviously, by increasing the number of contacts engaged by the switching device 101 the total capacity of the condenser could be increased to any desired value. The pin 102 which rotates with the switching device 101 is arranged to extend through a suitable 80 opening in casing 107 and is provided with an indicating arrangement 108 which cooperates with a suitable scale on the casing to indicate the number of 4 m. f. units which are connected between the line terminals. 90 The inner perimeter of this casing is also provided with a scale of the same type shown on Fig. 1 to indicate the capacity connected between terminals depending upon the position of the rotating member. 95

While this switch has been shown as used in connection with an adjustable condenser its construction is such as to be easily modified to serve equally well for connecting resistance units between a given pair of terminals, the same idea of picking up small units, and then dropping them again as a larger unit is picked up, being employed.

What is claimed is:

1. A multiple switch comprising a stationary member having a recessed portion therein, a plurality of contact members mounted in the recessed portion, a plurality of additional contact members mounted on the stationary member and in a different plane from said first contact members, and a movable member provided with separate means each of which in turn is adapted to consecutively engage the contact members mounted in the recessed portion until all such members are engaged, and additional means for engaging the contact members mounted in a different plane. 105
2. A multiple switch comprising an annular stationary member having a recessed portion therein, a plurality of contact members radially mounted in the recessed portion, a plurality of contact members mounted on the top of the stationary member, a movable member adapted to rotate within the stationary member, a plurality of conducting segments mounted in the periphery of said movable member for engaging the contact members located in the recessed portion, each of said segments in turn being 110 120 125 130 135 140 145 150 155 160 165 170 175 180

- adapted to engage the entire set of contact members and additional means for engaging the contact members mounted on the top portion of the stationary member, said means being in engagement with one of the top contacts upon the engagement of any one of said conducting segments with all of the contact members mounted in the recessed portion.
10. 3. A multiple switch comprising an annular stationary member having a recessed portion therein, a plurality of contact members radially mounted in the recessed portion, a plurality of contact members radially mounted on the top portion of the stationary member, a disc-shaped movable member adapted to rotate within the stationary member, a plurality of means on said movable member adapted to engage the contact members mounted in the recessed portion, and additional means electrically insulated from said other means to engage the contact members mounted on the top portion of said stationary member.
25. 4. A multiple switch comprising an annular stationary member having a recessed portion therein, a plurality of contact members radially mounted in the recessed portion, a plurality of contact members radially mounted on the top portion of the stationary member, an insulating disc adapted to rotate within the stationary member, a plurality of conducting segments mounted in the periphery of the insulating disc in a plane with the contact members mounted in the recessed portion of the stationary member, each of said segments being adapted upon rotation to simultaneously engage all of the contact members mounted in the recessed portion, and an additional conducting segment mounted in the rotating disc and in a plane with the contact members mounted on the top of the stationary member.
30. 5. A multiple switch comprising an annular stationary member having a recessed portion therein, a plurality of contact members radially mounted in the recessed portion, a plurality of contact members radially mounted on the top portion of the stationary member, an insulating disc adapted to rotate within the stationary member, a plurality of conducting segments mounted in the periphery of the insulating disc in a plane with the contact members mounted in the recessed portion of the stationary member, each of said segments being adapted upon rotation to simultaneously engage all of the contact members mounted in the recessed portion, and an additional conducting segment mounted in the rotating disc and in a plane with the contact members mounted on the top of the stationary member.
35. 6. A multiple switch comprising an annular stationary member having a recessed portion therein, a plurality of contact members radially mounted in the recessed portion, a plurality of contact members radially mounted on the top portion of the stationary member, an insulating disc adapted to rotate within the stationary member, a plurality of conducting segments mounted in the periphery of the insulating disc in a plane with the contact members mounted in the recessed portion of the stationary member, each of said segments being adapted upon rotation to simultaneously engage all of the contact members mounted in the recessed portion, and an additional conducting segment mounted in the rotating disc and in a plane with the contact members mounted on the top of the stationary member.
40. 7. A multiple switch comprising an annular stationary member having a recessed portion therein, a plurality of contact members radially mounted in the recessed portion, a plurality of contact members radially mounted on the top portion of the stationary member, an insulating disc adapted to rotate within the stationary member, a plurality of conducting segments mounted in the periphery of the insulating disc in a plane with the contact members mounted in the recessed portion of the stationary member, each of said segments being adapted upon rotation to simultaneously engage all of the contact members mounted in the recessed portion, and an additional conducting segment mounted in the rotating disc and in a plane with the contact members mounted on the top of the stationary member.
45. 8. A multiple switch comprising an annular stationary member having a recessed portion therein, a plurality of contact members radially mounted in the recessed portion, a plurality of contact members radially mounted on the top portion of the stationary member, an insulating disc adapted to rotate within the stationary member, a plurality of conducting segments mounted in the periphery of the insulating disc in a plane with the contact members mounted in the recessed portion of the stationary member, each of said segments being adapted upon rotation to simultaneously engage all of the contact members mounted in the recessed portion, and an additional conducting segment mounted in the rotating disc and in a plane with the contact members mounted on the top of the stationary member.

In witness whereof, I hereunto subscribe my name this 5th day of August, A. D. 1918.

AUGUSTUS J. EAVES.
